SAMPLE SHOE

Richard J. Jewett, Brockton, Mass.

Application November 27, 1935, Serial No. 51,759

14 Claims. (Cl. 35—57)

My invention relates to the manufacture of shoes and more especially to an improved form of sample shoe.

It is a practice of shoe manufacturers to obtain the styles embodied in their shoes from specialists who are highly skilled in shoe design, the manufacturer selecting from many styles submitted those which appear to best fit his needs. In submitting new styles of shoes to the manufacturer, the stylist provides patterns of the shoes, and especially of the shoe uppers which contain most of the distinctive features of the shoes, in many cases completely finished uppers being supplied which are pulled over lasts so that the shoe may be seen in its completed shape or form. As each manufacturer usually has his own distinctive shapes of lasts, it is not entirely satisfactory to display the new designs on more or less standardized lasts, but in the final determination of the desirability of the new styles the manufacturer is put to the necessity of cutting and assembling the uppers and pulling them over his own lasts.

This method of displaying shoe styles is relatively expensive and results in a considerable amount of waste, and if the stylist is submitting the samples on lasts of his own selection it requires the transportation of heavy and bulky lasts, together with the possibility that the lasting tacks may be dislodged, permitting the uppers to wrinkle or slip.

The usual method of displaying sample shoes or pull overs requires the use of a last as a part thereof, and if the sole and heel or other parts of the shoe are added to the uppers these are usually secured in some manner to the last, thus preventing the withdrawal of the last from the shoe. As a result it is impossible to determine the weight or the shape which the shoe will assume when separated from the last.

The principal object of the present invention is to provide a sample shoe, including an upper, which may be assembled on and which will adjust itself to fit lasts of varying shapes, without the necessity of pulling the uppers over the lasts and securing them thereto.

In a more specific aspect, it is an object of the invention to bring about a form of sample shoe which will not only accommodate itself to lasts of varying shapes and styles but which, when assembled thereon, will be free of undesirable wrinkles and other distracting imperfections.

Another object of the invention is to provide a sample shoe, and especially a shoe upper and inner sole construction, which not only may be

assembled on and will accommodate itself to lasts of varying shapes, but on which, if desired, a sole and heel or other shoe parts may be assembled in more or less usual manner to complete the shoe structure, the last, when the shoe is so completed, being freely withdrawable therefrom.

To these and other ends, the invention consists in the novel features and combinations of parts to be hereinafter described and claimed.

In the drawing.

Fig. 1 is a perspective view of a sample shoe, according to the invention;

Fig. 2 is a view of the under side of the shoe shown in Fig. 1;

Fig. 3 is a sectional view taken along line 3—3 of Fig. 2;

Fig. 4 is a view similar to Fig. 2 but in perspective, and showing a modification;

Fig. 5 is a view similar to Fig. 2 but showing another modification, and

Fig. 6 is a view similar to Fig. 2 but showing still another modification.

Referring now to the drawing, in which I have illustrated my invention by showing some preferred embodiments of the same, and with particular reference at present to Figs. 1, 2, and 3, the numeral 10 indicates, in general, the improved form of sample shoe, which comprises an upper, prepared in accordance with usual processes and pulled over a last 12, of usual form and not shown herein in detail. The upper 11 may be lined if desired although in most cases the presence of the lining is not necessary since it does not enter into the visual effect of the shoe.

The upper 11 is pulled tightly about the last 12, in usual manner, and the lower marginal edges 13, of the upper, are attached to the marginal edges 14 of an inner sole 15. In this instance the inner sole 15 is formed out of a sheet of elastic material, preferably sheet rubber, the inner sole 15 extending substantially from the toe 16, of the upper, to the heel 17 thereof, and completely filling the opening 18 at the bottom of the upper between the marginal edges thereof. Preferably the marginal edges of the upper are cemented to the inner sole, although it is within the invention to secure the upper to the inner sole in any desired manner.

The edges 19 and 20 of the upper 11, at the heel and toe, may be folded in the usual manner or, as in this instance, they may be slashed to form openings 21 which are bridged by the elastic inner sole 15, thereby giving the sample shoe greater elasticity of movement and adjustment at the heel and toe so that it may more readily ac-

commodate itself to the last at these points. In order to add to the elasticity of the sample shoe, and particularly the lower marginal edges thereof, the inner sole 15 may be made thinner at the 5 heel and toe, as indicated at 22 and 23 of Fig. 3.

After the upper has been attached to the inner sole 15, the last may be withdrawn and the sample shoe is ready for use in connection with other lasts which may vary to a considerable extent 10 in shape and size. When it is desired to display the shoe on the individual lasts of a manufacturer, the upper with the inner sole attached thereto is drawn over these lasts, the inner sole yielding to permit the upper to accommodate 15 itself to the lasts. It will be noted that the inner sole may be placed under tension and may yield from end to end of the last as well as transversely thereof, thus drawing the upper tightly about the last in all directions. After the sample shoe 20 has been assembled on any particular last, and the desirability of the style embodied therein has been demonstrated, it is a matter of routine manufacture to assemble a sole and heel thereon.

For example, an outer sole may be attached to 25 the upper according to the usual practices in making cemented shoes, in which case the inturned edges of the upper may be roughened to receive the cement. Any other suitable method may be used but as the attachment of the sole and heel 30 will suggest itself to anyone skilled in the art and does not form a part of the invention, it is not shown or described herein in detail.

In Fig. 4 of the drawings there is shown a 35 modification in which the usual seam, at the heel of the upper, is replaced by an insert 24 of elastic material which may be a part of the inner sole 25 or a separate element attached thereto. Although this insert is not necessary in the ordinary practice of the invention it will be found 40 useful in certain instances in order to give added elasticity to the upper as a whole and to assist in drawing the latter tightly about the last on which it is assembled. The inner sole 25, of this form of the invention, is substantially the same 45 as that of Figs. 1, 2, and 3, the toe 26 and the heel 27 of the marginal lower edges of the upper being in this case folded in usual manner before being attached to the inner sole 25.

In Fig. 5 there is shown another modification 50 differing from that shown in Figs. 1, 2, and 3, principally in that the inner sole 28 of elastic material is slit or otherwise opened at 29, from a point 30 adjacent the toe to a point 31 adjacent the heel, a slide fastener 32, of usual construction, being secured within the opening. It will 55 be readily understood that one of the rows of fastening elements is secured to the inner sole 28 at one of the edges of the opening 29, while the other row of fastening elements is secured 60 to the inner sole at the other edge of the opening. The details of the slide fastener are not shown herein as these devices are well known in the art. When it is desired to assemble this form 65 of the invention upon a last, the slide 33 is moved to one or the other of the ends of the opening 29 to disconnect the fastening elements. The inner sole is thus opened substantially from end 70 to end, and the upper may spread apart so that the last may be freely inserted within the upper, whereupon the slide 33 may be moved to bring 75 the fastening elements into locking engagement, thus bringing the inner sole under tension to draw the upper into tight engagement with the last.

In Fig. 6 still another modification of the invention is shown. In this instance the central

part of the inner sole is cut away for the insertion of a strip of leather or other relatively smooth preferably non-elastic material 34, the opening 35, formed in the inner sole 36, having edges spaced from and generally parallel to the lower edges of the upper, the insert 34 extending substantially from the toe 37 to the heel 38, of the inner sole. The meeting edges of the insert 34 and the inner sole 36 are sewed or otherwise secured together. The purpose of the insert is 10 to reduce the frictional contact of the last and inner sole during the insertion of a last, the latter sliding freely over the insert, whereas in some cases there is a tendency for the sheet rubber, of which the inner sole is preferably formed, to 15 cling to the last bottom. It will be noted that the insert is surrounded by the elastic inner sole so that the upper will be drawn into contact with the last about the entire peripheral surface of the latter. 20

From the above description of the several embodiments of the invention it will be readily understood that the elastic inner soles, forming a part of the invention, do not serve to prevent the bottom of the shoe from spreading, as is the 25 function of the usual inelastic inner sole. On the contrary the upper may adjust itself in any direction necessary to fit an individual last, the inner sole stretching or contracting to bring the upper into tight engagement with the last. It 30 will also be noted that neither the upper nor the inner sole are attached in any manner to the last so that the latter may be freely withdrawn at all times. At the same time the constructional details of the upper and the inner sole are such 35 that an outer sole and heel may be assembled on the upper in accordance with usual manufacturing methods.

By these means the uppers may be assembled 40 together with the inner soles and presented to a manufacturer for inspection on his own lasts and, if desired, may be finished into a complete shoe, from which the last may be readily withdrawn if necessary. In any event, whether used in the assembly of complete shoes or used in the manu- 45 facture of simple pull-overs, it will be apparent that the invention provides an arrangement wherein the usual pulling over and tacking steps of shoe making are avoided and greatly simplified and the fitting of the uppers to the lasts effected 50 in a simple manner.

While I have shown and described some preferred embodiments of the invention, it will be understood that it is not to be limited to the details shown, but is capable of modification and 55 variation within the spirit of the invention and the scope of the appended claims.

What I claim is:

1. A sample shoe comprising, an upper adapted to be assembled on a last, the lower marginal edge 60 portions of the upper being turned inwardly over the bottom of the last, and an inner sole of elastic yieldable material filling the opening formed at the last bottom between the marginal edges of the upper, the inner sole at its marginal edges 65 being attached to the inwardly turned marginal edge portions of the upper.

2. A sample shoe comprising, an upper adapted to be assembled on a last, and an inner sole of elastic yieldable sheet material closing the opening formed at the last bottom, said inner sole being attached to the lower edges of the upper about 70 the entire lower peripheral edge of the latter.

3. A sample shoe comprising, an upper adapted to be assembled on a last, the lower marginal edge 75

5 portions of the upper being turned inwardly over the bottom of the last, an inner sole of elastic yieldable material attached to the lower marginal edges of the upper at the heel and toe and along the sides thereof, there being an opening in the inner sole wholly within the marginal edges thereof to permit the free assembly of the upper together with the inner sole upon the last and means for closing the opening after assembly of 10 the shoe upon the last.

10 4. A sample shoe comprising, an upper adapted to be assembled on a last, and means at the shoe bottom and associated with the lower marginal edges of the upper adapted to yieldingly pull the 15 entire lower marginal edge portions of the upper inwardly across the bottom of the last to urge the upper into tight engagement with the last about the entire peripheral surface thereof.

15 5. A sample shoe comprising, an upper adapted to be assembled on a last, an inner sole formed out of elastic sheet material and closing the opening formed at the last bottom between the lower marginal edges of the upper, the inner sole being slit along a median line thereof, and a slide 20 fastener attached to the inner sole and adapted to close said slit.

20 6. A sample shoe adapted to be assembled on lasts of varying sizes and shapes comprising an upper, the lower marginal edges of the upper being turned inwardly over the last bottoms and means associated with the marginal edges of the upper at the bottom of the shoe adapted to yieldingly pull a variable amount of the inwardly turned marginal edges of the upper across the 30 bottoms of the lasts at the heel and toe and along the sides thereof to cause the upper to fit the particular last on which it is assembled.

30 7. A sample shoe comprising, an upper adapted to be assembled on a last, the lower marginal edges of the upper being turned inwardly over the last bottom, and an inner sole attached to the marginal edges of the upper at the heel and toe and along the sides, the inner sole comprising a 35 single sheet of yieldable elastic sheet material.

40 45 8. A sample shoe comprising, an upper adapted to be assembled on a last, the lower marginal edges of the upper being turned inwardly over the last bottom, and an inner sole attached to the marginal edges of the upper at the heel and toe and along the sides, the inner sole comprising a 45 single sheet of yieldable elastic sheet material, the inner sole being of less thickness at the heel and toe than along the sides thereof.

9. A sample shoe comprising, an upper adapted to be assembled on a last, the lower marginal edges of the upper being turned inwardly over the last bottom and an inner sole formed out of a single piece of yieldable elastic sheet material, the inner sole closing the opening formed at the last bottom between the marginal edges of the upper, the inner sole being attached to the marginal edges of the upper about the entire lower peripheral edge thereof. 10

10 15 10. The combination in a shoe of a flexible but substantially inelastic upper and an elastic yieldable shoe bottom adapted to yield lengthwise and transversely of the shoe to fit the upper to a last assembled therein.

15 11. The combination in a shoe having an upper of leather or other substantially inelastic material, the lower marginal edges of which are to be pulled over a last bottom, of means associated with the lower marginal edges of the upper for 20 yieldingly pulling the marginal edges of the upper across the bottom of the last as the latter is assembled in the upper.

20 25 12. The combination in a sample shoe of an upper of leather or other substantially inelastic material and an elastic yieldable inner sole attached to the upper, the inner sole prior to assembly on a last being of smaller size than normal for the specific last and being stretched by the upper upon assembly of the shoe on the last to place the 30 lower edges of the upper under tension to draw the upper into contact with the last.

30 35 13. A sample shoe comprising, an upper of leather or other substantially inelastic material adapted to be assembled on a last, and yieldable means attached to the upper at the bottom edges thereof adapted to be placed under tension by insertion of the last into the upper to draw the toe, heel and sides of the upper into tight engagement with the last. 40

40 45 14. A sample shoe comprising, an upper of leather or other substantially inelastic material adapted to be assembled on a last, and elastic means shaped to the shoe bottom and attached to the lower marginal edges of the upper to place the upper, when assembled on the last, under tension lengthwise and transversely of the shoe to pull the upper into contact with the peripheral surface of the last. 45
